UNITED STATES PATENT OFFICE.

CHARLES OTTINGER, OF PHILADELPHIA, PENNSYLVANIA.

DESIGN FOR A HAMMER.

SPECIFICATION forming part of Design No. 19,689, dated March 4, 1890.

Application filed December 28, 1889. Serial No. 335,282. Term of patent 14 years.

To all whom it may concern:

Be it known that I, CHARLES OTTINGER, a citizen of the United States, residing at Philadelphia, in the county of Philadelphia and 5 State of Pennsylvania, have invented a new and useful Design for Combined Peen and Bush Hammers, of which the following is a specification.

The invention relates to a new and original 10 design for a hammer.

The figure of the drawing is a perspective view of the hammer showing my new design.

The essential feature of this design resides in the peculiar shape of the ends or faces of 15 the hammer.

Referring to the drawing, 1 designates a hammer-head, which is approximately rectangular and is provided with a central vertical

opening. The hammer-head is provided at its ends with rectangular recesses. One end 20 or face of the hammer has curved edges and the other face or end has a series of beveled edges.

What I claim is—

The design for a hammer herein shown, the 25 same consisting of the rectangular head having at one end a face with curved edges and at the other end a face provided with a series of beveled edges, as set forth.

In testimony that I claim the foregoing as 30 my own I have hereto affixed my signature in presence of two witnesses.

CHARLES OTTINGER.
